(57) **CLAIM**

The ornamental design for a tread of an automobile tire, as shown and described.

DESCRIPTION

FIG. 1 is a perspective view of a tread of an automobile tire showing my design;

FIG. 2 is a front view thereof;

FIG. 3 is a right side view thereof;

FIG. 4 is a left side view thereof;

FIG. 5 is a rear view thereof;

FIG. 6 is a fragmentary enlarged front view surrounded by line A-A and B-B in FIG. 2;

FIG. 7 is a sectional view taken along line 7-7 in FIG. 6;

FIG. 8 is a sectional view taken along line 8-8 in FIG. 6; and,

FIG. 9 is a section view taken along line 9-9 in FIG. 6.

The broken lines in the drawings show portions of the tire that are not being claimed and thus form no part of the claimed design.
